GLOBE MOUNTING

John A. Pinaud, Atlantic Highlands, N. J., assignor to Rand McNally & Company, New York, N. Y., a corporation of Illinois

Application January 28, 1933, Serial No. 654,036

10 Claims. (Cl. 35—46)

This invention relates to improvements in supports and more specifically to an improved support or mounting for terrestrial globes and the like.

5 An object of this invention is to provide a novel and improved support for a globe allowing thereby a very satisfactory and complete means of handling and moving the globe.

10 It is also an object of this invention to provide improved supporting and gripping guide members for a globe assembly, and more particularly for the annulus thereof.

15 Yet a further object of this invention is the provision of improved semi-resilient guide members adapted for insertion in yokes and which function to retain the globe at any desired longitudinal setting and which are adapted further to be locked in any given position.

20 These and other desirable objects and advantages of the present invention will be described in the accompanying specification and illustrated in the drawing, certain preferred improvements being illustrated by way of example only, for, since the underlying principles may be incorporated in other specific mechanical structures, it is not intended to be limited to the ones here shown except as such limitations are clearly imposed by the appended claims.

25 Referring more specifically to the drawing:

30 Fig. 1 is a front elevation of a globe mounted on a standard;

35 Fig. 2 is a detail of the upper portion of the standard and associated yoke and scale members;

40 Fig. 3 is a vertical section taken on line 3—3 of Fig. 2, showing details of the locking mechanisms;

45 Fig. 4 is a horizontal section taken on line 4—4 of Fig. 1;

50 Fig. 5 is an exploded view of the improved locking mechanism shown in Figs. 3 and 4;

55 Fig. 6 is an elevation of an arc guide in position on an end of the yoke arm; and

60 Fig. 7 is an elevation of a modified, threaded, dished locking ring.

Referring more specifically to the drawing, there is shown a terrestrial globe assembly comprising a globe 10 mounted for rotation on a polar axis 20, secured to the graduated annular supporting member 21 of preferred I-cross section. The globe is supported by means of the annulus 21 satisfactorily positioned in a combined hand hold and yoke member 30. This latter is provided with a dependent boss portion 31 having an aperture 32 adapted to receive the head 41 of the standard 40. A base 42 of any suitable configuration is associated with the standard 40 and serves to retain the globe assembly in a desired position.

As has been noted hereinabove, it has been customary for globes to be mounted loosely upon a standard. A particular feature of novelty of the present invention resides in the use of an improved demountable locking means for maintaining the globe assembly locked to the standard and, at the same time permitting revolution of the globe assembly about the standard. The improved means for accomplishing this result preferably comprises channeled section 43 formed in 10 the upper portion of the standard 40, which channel is adapted to receive the locking bolt 50 which is provided with a spindle engaging head portion 51 and a collar or retaining member 52 adapted to serve as a support or point of resistance for a 15 spring member 53. The spring 53 is nested in a dished member 54 of a suitable deformable metal such as brass, the said member being apertured to receive the shank of member 50. The member 54, in conjunction with the section 52 of the 20 rod 50, serves to retain the spring in position and permit it to force the locking bolt into the channel 43 of the member 40. Thus it will be seen that by this simple, effective means the globe assembly is permanently locked on the standard 25 40 and the said assembly and standard may be lifted and transported as a unit without requiring that the lifting force be applied solely to the standard. The exterior portion of the bolt 50 may be grooved, as indicated at 55, to provide a 30 finger grip which will permit the ready withdrawal of the bolt section 51 from the channel 43 so that the globe and associated yoke member 30 may be lifted off the standard 40 by hand. The member 54 may be externally threaded as 35 shown at 54a in Fig. 7 to permit threaded engagement with its socket instead of being press-fitted therein.

The improved bolt mechanism is adapted to be fitted into a suitable aperture 56 in the boss 31. 40 The upper end of the standard 40 may be suitably configured, as indicated at 44, to engage the bearing surface 33, formed at the upper end of the aperture 32. This bearing surface may be conical in shape or may have any other desired 45 configuration.

As has also been noted hereinabove, a difficulty has been experienced previously with means for rotating the graduated arcuate member 21 in position. Normally these members are made of 50 a flat annulus suitably graduated and serve as supports for the polar axis. However, the yoke supports have been used to give a full bearing surface and such bearing surfaces have been loose so that considerable play in the globe has 55 been encountered. To overcome this, the improvements of the present invention comprehend a three point support, indicated generally as two end supports 35 and 36, together with a bottom central support or boss 37, all being preferably 60

formed integrally with the yoke member 30. The three-point support provided by these members, has its utility further enhanced by the provision of improved bushings 60 of semi-vulcanized rubber or other like materials which, while permitting the ready movement of the annulus 21 therethrough, at the same time provide a sufficient grip for the said annulus so as to prevent any undesired and uncontrolled movement thereof or noise. With other constructions considerable noise is made, and it is desired to eliminate any noise.

The members 60 comprise a generally U-shaped member having a side wall portion 61, a bottom 15 62 and a depending block portion 63. The side walls 61 are adapted to conform to the channel formed in the members 35, 36, 37 and the stub portions 63 are adapted to grippingly engage holes or depressions 38 formed in the member 30. Preferably, the members 60 are press-fitted in place, thus insuring accurate alignment and permitting the annulus 21 to be accurately aligned and grippingly held. The member 21, as noted above, is generally I-shaped, being provided with 20 top and bottom bar members 22, formed integrally therewith. These members or sections may have any desired configuration whatsoever.

To support the setting of the supporting annulus 21 at any desired point, the said annulus 30 may be locked in position by any suitable means such as a locking screw or equivalent member 65. This is preferably inserted in the boss portion 37 of the support 30 and, due to the formation of at least the bottom section 22 of the annulus, provides a positive retaining lock for the said member and the associated globe. The annulus, with its associated globe, may be thus rotated normally to its polar axis to any desired degree of angularity and thereafter locked in 35 position by means of the member 65. To change the setting of the annulus 21, the member 65 is loosened and the desired change in setting made, after which the screw is again tightened, locking the assembly in place.

It will now be appreciated that there has been 40 provided an improved globe assembly which is mounted for universal rotating in any direction, which assembly includes novel locking means for retaining the globe supporting yoke on a standard, yet at the same time permitting the removal of same when desired. In addition, there has been disclosed novel gripping and guiding members for the globe supporting annulus which permits the ready movement of the latter without noise and at the same time doing away with vibration and play.

While certain novel features of the invention have been disclosed and are pointed out in the annexed claims, it will be understood that various 45 omissions, substitutions and changes may be made by those skilled in the art without departing from the spirit of the invention.

What is claimed is:

1. An improved support for a globe, comprising 50 a supporting annulus for the said globe, and means for grippingly supporting the said annulus in a desired position, said means comprising at least three resilient members mounted in the yoke and adapted to form at least a three-point support.

2. An improved yoke member for globe assemblies adapted to be mounted on a standard, comprising, in combination, a semi-circular mem-

ber, a boss formed at the exterior central portion of the said semi-circular member, a plurality of resilient gripping members symmetrically disposed interiorly of the semi-circular member and a locking member formed in the said boss, 5 said boss being adapted to serve as a hand hold for manually supporting the globe when dismounted from a standard.

3. An improved gripping member for use in globe supporting members comprising a U-shaped 10 member of resilient material and having a depending fastening stud formed integral with the bottom portion of the U.

4. An improved gripping member for use in globe supporting members comprising a U-shaped 15 member of semi-vulcanized rubber and having a depending fastening stud formed integral with the bottom portion of the U.

5. An improved support for a globe, including; a yoke adapted to be mounted on a standard; 20 and means adapted to grippingly support an annulus having a globe revolvably mounted therein on a polar axis, said means comprising at least three resilient gripping members mounted in the yoke and adapted to form a three-point support 25 for said annulus.

6. An improved support for a globe, including; a yoke adapted to be mounted on a standard; and means adapted to grippingly support an annulus having a globe revolvably mounted therein on 30 a polar axis, said means comprising at least three U-shaped members of resilient material mounted on said yoke, said members being adapted to yieldingly engage said annulus to form at least a three-point support therefor.

7. An improved support for a globe, including; a yoke adapted to be mounted on a standard; and means adapted to grippingly support an annulus having a globe revolvably mounted therein on 35 a polar axis, said means comprising U-shaped 40 members of resilient material mounted on said yoke, said members being adapted to receive said annulus therein and to yieldingly engage the sides thereof, whereby the annulus may be manually adjusted.

8. An improved gripping member for use in a globe supporting member comprising a U-shaped member of resilient material having a fastening stud depending from the bottom portion of the U.

9. An improved gripping member for use in a globe supporting yoke comprising a U-shaped member of resilient material having a stud depending from the bottom portion of the U, said stud being adapted to be received by an opening in said yoke, said member being adapted to yieldingly engage an annulus having a globe revolvably mounted therein.

10. An improved globe assembly adapted to support a globe revolvably mounted on a polar axis in an annulus, comprising means for grippingly and yieldingly supporting the said annulus in a desired annular position, said means comprising at least three resilient members mounted in a yoke and adapted to form at least a three-point support for said annulus, said yoke being provided with a dependent apertured boss adapted to receive the top of a standard, and spring-urged locking-means associated with said boss for demountably maintaining said yoke secured to said standard, said locking-means being adapted to engage an annular locking-recess in the top of said standard.

JOHN A. PINAUD.
